Patented Nov. 7, 1916.

UNITED STATES PATENT OFFICE.

JAMES MILLBOURN, OF NEW YORK, N. Y., ASSIGNOR TO GAS ENGINE & POWER CO.
AND CHARLES L. SEABURY & CO., CONSOLIDATED, OF NEW YORK, N. Y., A COR-
PORATION OF NEW YORK.

HYDROCARBON-BURNER.

1,204,051.

Specification of Letters Patent.

Patented Nov. 7, 1916.

Application filed December 31, 1914. Serial No. 879,909.

To all whom it may concern:

Be it known that I, JAMES MILLBOURN, a citizen of the United States, and a resident of the city of New York, borough of Bronx, in the county of Bronx and State of New York, have invented a new and Improved Hydrocarbon-Burner, of which the following is a full, clear, and exact description.

10 My invention relates to hydrocarbon burners mainly intended for the consumption of alcohol as a fuel.

15 The object of the invention is to provide a simple, strong and inexpensive burner which has a high efficiency.

20 With the above and other objects in view, the nature of which will more fully appear as the description proceeds, the invention consists in the novel construction, combination and arrangement of parts as herein 25 fully described, illustrated and claimed.

25 In the accompanying drawings, forming part of the application, similar characters of reference indicate corresponding parts 30 in all the views, and Figure 1 is a side elevation of an embodiment of my invention; Fig. 2 is a cross section thereof on line 2—2, Fig. 1; Fig. 3 is a horizontal section on line 3—3, Fig. 2; Fig. 4 is a cross section 35 on line 4—4, Fig. 1; Fig. 5 is a longitudinal section through the needle valve controlling the feed of the fuel to the mixing chamber; Fig. 6 is a cross section through the wick; Fig. 7 is a cross section through a modified 40 structure of the wick; and Fig. 8 is an elevation thereof.

45 Referring to the drawings, A is a retort wick formed of a metallic gauze fabric 9 of very thin mesh wound on a central rod 10. The rod 10 projects at both ends of the said roll of gauze wound about it; and at one end the roll is clamped by the end of the rod to the rod. The gauze roll can be secured to the other end of the rod in any 50 suitable way; as shown, it is tied to the rod 10 by a wire 11. The end of the rod adjacent the wire 11 is in the shape of a hook, so that the same can be easily engaged for manipulation. The diameter of the roll of 55 gauze 9 is substantially equal to the diameter of the vaporizing chamber 12, the rear end of which is connected to the alcohol-supply pipe 13. At the front end the vaporizing chamber is provided with a plug 14 which

controls the access to the said vaporizing 55 chamber and permits the removal or insertion of the wick. By providing the plug 14 at the front end of the burner, it is not necessary to disconnect the burner from the fuel-supply pipe every time it is desired to inspect the wick or to clean the same.

The vaporizing chamber 12, adjacent the front end, is provided with a tubular portion 15 extending parallelly to the vaporizing chamber to accommodate the needle 65 valve 16 which controls the outlet of the gasified fuel coming from the vaporizing chamber to the tubular portion 15. The gaseous fuel is directed by the needle valve 16 into a mixing conduit 17 spaced from 70 the conduit 15 by an air gap. The said mixing conduit 17 leads to a mixing chamber 18, preferably of cylindrical form and connected to the vaporizing chamber by suitable brackets 19. The said mixing chamber 75 18 is apertured, as best seen in Fig. 3, and forms the burner proper. It will be noted that the wick A extends substantially through the entire length of the vaporizing chamber and over the passage leading to the 80 tubular portion 15. The chamber 18 has additional perforations 21 on the side thereof below the vaporizing chamber, whereby heat is positively supplied to the vaporizing chamber. The heat of the fuel burning at 85 85 the perforations of the mixing chamber will easily gasify the fuel sub-divided into minute particles by the gauze forming the wick. It is self-evident that by forming the wick 90 from gauze the fuel is split up into minute particles exposed on an exceedingly large surface; and under the action of heat the same will readily gasify and thus a uniform feed of gaseous fuel will flow through the outlet in the tubular portion 15 95 controlled by the needle valve 16. Thus, a greater economy of fuel is obtained and a more efficient burner results.

Secured to the mixing chamber and positioned below the same is a heating pan 21 100 which extends with one end thereof beyond the gap between the tubular portion 15 and the mixing conduit 17. The heating pan has an overflow 22 directed to a closed receptacle and normally preventing the alcohol from flowing over the edges of the pan around the burner and causing fire, due to 105 the inattention of the operator. The alco-

hol is normally supplied to the pan by the needle valve, as before the vaporizing chamber is heated the alcohol flows through the needle valve in liquid form and not in the 5 form of gas.

In burners of large diameters, in lieu of using a roll of gauze wound on a rod, as shown in Fig. 6, a gauze container 20 may be formed supported by a rod 10', and which 10 container may be filled with mineral wool, or other similar substance, to cause the fuel passing therethrough to be sub-divided into minute particles disposed on a large area.

Having thus described my invention, I 15 claim as new and desire to secure by Letters Patent:

In a hydrocarbon burner, a tubular vaporizing chamber, a branched-out conduit from said vaporizing chamber, a needle valve 20 controlling the outlet from said conduit, a mixing conduit adapted to receive the fuel controlled by the needle valve and separated

from said branching-out conduit by an air gap, a tubular mixing chamber associated with the mixing conduit, said mixing chamber having perforations on the lateral surface thereof, means connecting said vaporizing chamber to said mixing chamber adjacent the perforations, a metallic gauze fabric roll in said vaporizing chamber between the fuel supply and the branching-out conduit, and a heating pan below the mixing chamber and extending beyond the air gap to receive fuel from the branching-out conduit, said pan having an overflow leading 35 to a closed receptacle substantially as and for the purpose set forth.

In testimony whereof I have signed my name to this specification in the presence of two subscribing witnesses.

JAMES MILLBOURN.
